DESIGN FOR AN ELECTRIC MOTOR

Carlos B. Livers, North Hollywood, Calif., assignor to Variety Development and Engineering Company, Los Angeles, Calif., a co-partnership composed of Carlos B. Livers and Ralph E. Middleton

Application December 16, 1946, Serial No. 135,542

Term of patent 3½ years

(Cl. D26—5)

To all whom it may concern:

Be it known that I, Carlos B. Livers, a citizen of the United States and resident of North Hollywood, in the county of Los Angeles and State of California, have invented a new, original, and ornamental Design for an Electric Motor, of which the following is a specification, reference being had to the accompanying drawing, forming part thereof.

Figure 1 is a plan view of an electric motor, showing my new design.

Figure 2 is an elevational view from the left side of Figure 1.

Figure 3 is an elevational view from the lower side of Figure 1.

Figure 4 is an elevational view from the right side of Figure 1.

Figure 5 is an elevational view from the top side of Figure 1.

I claim:

The ornamental design for an electric motor, as shown.

CARLOS B. LIVERS.
